UNITED STATES PATENT OFFICE.

HARRY N. MIDDLETON, OF WESTVILLE, NEW JERSEY, ASSIGNOR OF ONE-HALF TO CHARLES H. GIFFORD, OF PHILADELPHIA, PENNSYLVANIA.

HOOD FOR GRINDING AND POLISHING WHEELS.

SPECIFICATION forming part of Letters Patent No. 787,340, dated April 11, 1905.

Application filed December 14, 1903. Serial No. 185,133.

To all whom it may concern:

Be it known that I, HARRY N. MIDDLETON, a citizen of the United States, and a resident of Westville, Gloucester county, New Jersey, have invented certain Improvements in Hoods for Grinding and Polishing Wheels, of which the following is a specification.

My invention relates to certain improvements in hoods for grinding and polishing wheels which are connected to exhaust-fans.

The object of my invention is to prevent the passage of heavy particles from the hood to the exhaust-fan, which are ordinarily injurious to the fan. This object I attain by providing a collector in the hood which receives the heavy particles of material and prevents their escape to the fan.

My invention relates, further, to the particular construction of the hood, as fully described.

In the accompanying drawings, Figure 1 is a perspective view of my improved hood, illustrating one form of the invention. Fig. 2 is a side view, and Fig. 3 is an end view.

A is a hood having a curved portion *a*, which fits over the grinding or polishing wheel. (Shown by dotted line *x*, Fig. 1.) This curved portion connects with the body of the hood.

Below the grinding-wheel in the present instance is a chamber or receptacle B, having a removable cap B', which is connected to the body by a bayonet-joint *b*; but other means of fastening the cap to the body portion may be resorted to without departing from my invention.

A' is the outlet from the hood, which is connected to a suction or exhaust fan of any suitable type.

Pivoted at *d* to the front of the hood is a plate D, having side members *d'* *d''*. The side member *d'* is hinged to the plate D, so that it can be turned back for the purpose described hereinafter. Carried by the plate D is a slide D', which can form an extension of the plate when desired.

The object of hinging the plate D is to al-

low it to be moved toward the wheel as it is reduced in diameter by wear.

The side plate *a'* of the body of the hood is fixed, while the opposite side plate *a''* is hinged at *c* to allow it to be turned down for the removal of the grinding or polishing wheel from its shaft. The side member *d'* is hinged to the plate D for the same purpose. The side member *a''* of the body portion is attached to the body by a hook *c'* or any other suitable fastening.

On the outer end of the curved portion of the hood is a bracket *f*, to which is pivoted a shield F, which can be adjusted toward or from the surface of the wheel to catch any particles that fly from the wheel, so that they will be sure to be conveyed into the hood. The shield is held in its adjusted position by a set-screw *f'*.

While I have shown the hood in the particular form illustrated in Fig. 1 and the suction-pipe arranged at an angle, it will be understood that the receptacle for the solid matter may be of any shape desired, and the suction-pipe can be arranged at any angle.

It will be seen that my invention can be readily applied to any grinding or polishing machine to catch the particles of solid matter passing from the wheel. The particles fall to the bottom of the receptacle and are there collected, the suction not being sufficient to remove the particles which enter the receptacle. Consequently they will accumulate therein and can be removed at intervals by detaching the cap B'.

I claim as my invention—

1. A hood for grinding and polishing wheels, having a curved portion partly surrounding the wheel, a receptacle at the lower end of the hood, a detachable cap for the said receptacle, and an exhaust-pipe coupled to the hood at a point between the wheel and the receptacle, substantially as described.

2. The combination in a hood for grinding and polishing wheels, having a curved portion inclosing the wheel, a tapered body portion terminating in a receptacle, and an ex-

haust-pipe coupled to the body portion, with a detachable bottom for the receptacle, substantially as described.

3. The combination in an exhaust-hood for grinding and polishing wheels, of a casing having a receptacle formed therein, one side of the casing above the receptacle being hinged, a plate pivoted to the front of the body portion, and an exhaust-pipe connected to the casing above the receptacle, substantially as described.

4. The combination in an exhaust-hood for grinding and polishing wheels, of a body

portion having a receptacle at its lower end, an exhaust-pipe, a shield pivoted to the upper end of the body portion and extending partly over the wheel, and means for locking said shield in its adjusted position, substantially as described.

In testimony whereof I have signed my name to this specification in the presence of two subscribing witnesses.

HARRY N. MIDDLETON.
